US00D447279B1

(12) **United States Design Patent** (10) Patent No.: **US D447,279 S**
Altobellis et al. (45) Date of Patent: **** Aug. 28, 2001**

(54) **LOTION APPLICATOR WITH HINGED HANDLE**

Product packaging (front and back) for Suncare Applicator.

(75) Inventors: **Richard M. Altobellis; Douglas K. Ewald**, both of Boulder; **John L. Knight, Jr.**, Vail; **David B. Shaffer**, Lakewood, all of CO (US)

* cited by examiner

(73) Assignee: **Sunglider, Inc.**, Denver, CO (US)

Primary Examiner—Paula A. Mortimer

(74) Attorney, Agent, or Firm—Sheridan Ross P.C.

(**) Term: **14 Years**

(57) **CLAIM**

(21) Appl. No.: **29/131,974**

The ornamental design for a lotion applicator with hinged handle, as shown and described.

(22) Filed: **Oct. 30, 2000**

DESCRIPTION

(51) LOC (7) Cl. **28-02**

FIG. 1 is a front perspective view of a lotion applicator with hinged handle showing our new design;

(52) U.S. Cl. **D28/7**

FIG. 2 is a front perspective view of the invention illustrated in FIG. 1, with the handle shown in the folded position;

(58) Field of Search D28/7, 63; D32/40; D4/121, 137; 206/229; 15/144.1, 144.3, 144.4, 244.1, 244.2, 210.1, 222, 143.1

FIG. 3 is a right end elevation view of the invention illustrated in FIG. 1, the broken lines representing environment and forming no part of the claimed design;
